FIG. 1

FIG. 2.

FIG. 3

FIG. 1 is a fragmentary side elevational view of a wheel showing our new design, it being understood that the sides and top of the rim have been broken away for convenience of illustration;

FIG. 2 is a cross-sectional view thereof taken on the line 2—2 of FIG. 1 and looking in the direction of the arrows; and

FIG. 3 is an end elevational view thereof.

This application is a division of design application Ser. No. 262,948, filed June 15, 1972, and now Pat. No. D229,558, and a continuation-in-part of design application Ser. No. 191,579, filed Oct. 21, 1971, and now abandoned.

We claim:

The ornamental design for a wheel, as shown and described.
